UNITED STATES PATENT OFFICE.

ALBERT HUDZIAK, OF FRONTIER, WYOMING.

SOLDIER'S PROTECTOR.

1,273,371.

Specification of Letters Patent. Patented July 23, 1918.

Application filed March 22, 1918. Serial No. 223,944.

To all whom it may concern:

Be it known that I, ALBERT HUDZIAK, a citizen of the United States of America, residing at Frontier, in the county of Lincoln and State of Wyoming, have invented certain new and useful Improvements in Soldiers' Protectors, of which the following is a specification.

The primary object of the invention is the provision of a bullet protector arranged to be conveniently carried by a soldier to be set up for use in holding off bullets while firing upon the enemy.

A further object of the device is the provision of a foldable shield adapted for making bullets glance off from the same when set up for use, the structure being arranged for positioning upon the ground in the form of a barrier to accommodate a soldier positioned behind the same for firing through the barrier forwardly thereof.

With these general objects in view and others that will appear as the nature of the invention is better understood, the same consists in the novel construction, combination and arrangement of parts hereinafter fully described, illustrated in the accompanying drawing and pointed out in the appended claims.

30 In the drawing forming a part of this application and in which like numerals refer to corresponding parts throughout the several views:

Figure 1 is a rear perspective view of the 35 device in its spreadout arrangement;

Fig. 2 is a top plan view thereof;

Fig. 3 is an enlarged detail sectional view through one of the retaining clips; and

40 Fig. 4 is a sectional view thereof taken upon line 4—4 of Fig. 3.

It being understood that the device is in the nature of a bullet shield, the same consists of two arcuate plates 10 and 11 formed of bullet-proof material and being of equal 45 size, the said plates being connected by hinges 12 and 13 at their adjacent ends. A strap 14 connects the two plates 10 and 11 together limiting their outward movement upon the said hinges 12 and 13 and whereby 50 the device may be positioned in V-shaped arrangement as shown in Fig. 2 of the drawing having a pointed end or nose 15. The device may be readily carried upon the back of a soldier with the strap 14 positioned 55 around his neck while a retaining belt 16 is carried by the section 11 having an en-

gaging buckle 17 upon the section 10 for convenience in securing the device upon the soldier for carrying the same from place to place.

When it is desired to use the device as a shield, the same is positioned upright on the ground and long hooks 18 carried by each of the plates 10 and 11 are released from securing clips 19 upon the said plates and are swung into engagement with oppositely positioned eyes 20 carried by the said plates for this purpose. A pentagonal opening or loophole 21 is arranged in the nose 15 of the device for convenience in firing there-through upon the enemy positioned forwardly of the device. By releasing the hooks 18 and drawing the plates 10 and 11 inwardly toward each other the area of the opening 21 will be diminished or in other 70 words, the drawing toward each other of the opposite three-sided walls 22 of the opening 21 presents a smaller opening through which the bullets of the enemy can pass. The size of the opening 21 is regulated in this manner 75 by the soldier having charge of the shielding device, the opening 21 being the largest when the plates 10 and 11 are outstretched to the limit of their relative movement. It will be understood that the sides 22 of the opening 80 21 are in the form of cutout portions in the adjacent edges of the plates 10 and 11 so that the hinges 12 and 13 are positioned upon opposite sides of the opening, above and below the same.

The device may be constructed of metal that is light in weight and the shields may be transported in trucks to a convenient point requiring them to be carried only short distances by the soldiers, and being readily 90 set up for use and adjusted the same are adapted for preventing loss of life while permitting the soldiers to readily fire upon the enemy.

What I claim as new is:—

1. A bullet shield comprising a pair of rectangular plates arcuate in horizontal section and having cut-away portions in their adjacent vertical edges forming a firing opening in the device, said plates being positioned in substantially V-shaped arrangement when operatively positioned, hinge connections between the adjacent vertical edges of the plates arranged at opposite sides of the opening, the sides of said opening being adjustable by swinging the plates upon said hinge connections whereby the 100 105 110

area of the opening is varied, a pair of carrying straps connected between said plates to limit separation thereof, positioning hooks arranged between said plates, and means to 5 retain the hooks in substantially vertical inoperative position.

2. In combination, two rectangular plates arcuate in horizontal section and adapted to be positioned in substantially V-shaped arrangement when in use, spaced hinge connections between the adjacent vertical edges of said plates, said plates having a firing opening therein between said hinged connections, positioning hooks swingingly carried 10 by the plates adjacent their free ends, keepers for said hooks, spring clips carried by the plates to receive and retain said hooks in substantially vertical position when not in use, and flexible carrying means for the 15 plates to limit the separation of the latter.

3. A bullet shield including a pair of rectangular plates arcuate in horizontal section and hingedly connected at their adjacent

vertical edges, said plates being adapted for arrangement in substantially V-shaped formation when in use and having a firing opening therethrough at the connected edges thereof, a hook member hinged to one of said plates at the upper outer corner thereof, a second hook member hinged to the lower 25 outer corner of the other plate, a keeper carried by the first named plate at the lower outer corner thereof and engageable by the second named hook member when the plates are in operative position, a second keeper 30 carried by the second named plate at the upper outer corner thereof and engageable by the first named hook member when the plates are in operative position, and a clip carried by each of said plates between the 35 outer corners thereof to retain the hook member hinged thereto in substantially vertical position adjacent the inner face of said plate.

In testimony whereof I affix my signature.

ALBERT HUDZIAK.
